[57] CLAIM

The ornamental design for a radon monitor, as shown and described.

DESCRIPTION

FIG. 1 is a top and front perspective view of a radon monitor showing my new design;

FIG. 2 is a top plan view;

FIG. 3 is a front elevational view, the rear elevational view being a mirror image;

FIG. 4 is a left side elevational view, the right side elevational view being identical; and

FIG. 5 is a bottom plan view thereof.

The back side is identical in appearance to the front side and the left side is identical in appearance to the right side.

Fig. 1

*Fig. 2**Fig. 3*

*Fig. 4**Fig. 5*
